UNITED STATES PATENT OFFICE.

ALBERT F. WARD, OF SAN FRANCISCO, CALIFORNIA.

ADVERTISING DEVICE.

Application filed November 2, 1921. Serial No. 512,305.

To all whom it may concern:

Be it known that I, ALBERT F. WARD, a citizen of the United States, residing at the city and county of San Francisco and State of California, have invented new and useful Improvements in Advertising Devices, of which the following is a specification.

This invention relates to an advertising device, and especially to a mechanical or changeable picture.

The object of the present invention is to generally improve and simplify devices of the character described, and especially to provide a mechanically assembled picture, one or more portions of which may be moved to produce changeable effects, or otherwise attract the attention of passerbys or users for the purpose of advertising, amusing, etc.

Other objects will hereinafter appear.

The invention consists of the parts and the construction, combination and arrangement of parts as hereinafter more fully described and claimed, having reference to the accompanying drawings, in which—

Fig. 1 is a front view of the invention, showing it applied to an ordinary calendar.

Fig. 2 is a similar view showing the front plate of the calendar removed and disclosing the mechanism whereby movement is imparted to the changeable portions of the picture.

Fig. 3 is a central, vertical, longitudinal section taken on line 3—3, Fig. 1.

Fig. 4 is a perspective view of the intermediate plate.

Fig. 5 is a perspective view on one of the movable frame plates.

Fig. 6 is a perspective view of the other movable plate.

Referring to the drawings in detail, and particularly to Figs. 1 and 2, it will be seen that the invention has been applied to an ordinary calendar. The front of the calendar consists of a plate constructed of paper or any other suitable material, as indicated at A, upon which is printed, painted or otherwise formed a picture; for instance, of a baby, as illustrated at 2. Formed in this front plate A are three openings, as indicated at 3, 4 and 5. The openings 3 and 4 register with or form the eyes of the picture, while the opening 5, which is rectangular in shape, is disposed behind the calendar indi-

cated at 6 for purposes to be hereinafter described.

The whole device in reality consists of three main plates, the front plate A, an intermediate plate B, and a rear plate C. The rear plate is solid and has no openings formed therein. The intermediate plate has a large rectangular shaped opening formed therein as indicated at 7, while the front plate has the openings 3, 4 and 5 formed therein. When the three plates are assembled as shown in Fig. 3, it can be seen that a pocket or chamber is formed within the intermediate plate as indicated at 7. This pocket or recess is provided for the reception of a pair of frame plates generally indicated at D and E. The plate D is rectangular in shape; its width is identical to the width of the pocket or recess 7 so that no side movement may be imparted thereto, but the length of the plate D is slightly less than the length of the recess 7 so that a space 8 is formed; said space being provided to permit vertical or endwise movement of the plate D. The interior of the plate D is cut away to form an I shaped recess F. This recess is identical in shape to the plate E, which is placed therein. The plate E is however a little narrow when compared to the recess F and sufficient space is therefore left as indicated at 9, 10 and 11, to permit lateral movement of the plate E with relation to the plate D. The intermediate plate B and the plates D and E assume the same plane as the plate D, is movable within the recess 7, and similarly the plate E is movable within the recess formed in the plate D. The two plates indicated at D and E are thus secured against removal when the top plate A is applied, but endwise movement may be imparted to the plate D as the space 8 permits such movement, while lateral movement may be imparted to the plate E, as the spaces indicated at 9, 10 and 11 permit such movement.

To impart movement to the respective plates D and E, the calendar 6 is made use of. This calendar is secured to the plate E by means of a spacing block or plate 12. This block extends through the opening 5 and as it is smaller than the opening 5, it can be seen that vertical and lateral movement may be imparted to the plates D and E, through means of the calendar. In order

to attract attention to the calendar, for purposes of amusement, advertising or otherwise, a pair of eyes, such as shown at 14, are printed, painted or otherwise formed 5 on the upper end of the plate E. The eyes are so positioned as to substantially register with the openings 3 and 4 in the front plate A, and they are so arranged that when vertical and lateral movement is transmitted to 10 the plates E and D, a life-like movement may be given to the picture as the eyes appear to move with relation to the openings 3 and 4. In fact side movement may be imparted to the eyes, up and down movement 15 may be imparted thereto, and rolling movement, if desired, as the vertical and lateral movement of the plates D and E permit universal movement within a limited range. This movement, as previously stated, is imparted by grasping the calendar 6 and moving 20 it in any direction desired, and this movement is transmitted through the block 12 and plates E and D as the calendar is secured to the block 12, and this in turn is 25 secured to the plate E.

While the present invention shows a picture in which the eyes are movable, it is obvious that it may be changed to move any portion of the picture desired, and similarly 30 that movement may be imparted to one or more portions of the picture simultaneously. Further, while the device is shown as applied to a calendar, it may be applied to any picture or object desired. I also wish it 35 understood that the materials and finish of the several parts employed may be such as the experience and judgment of the manufacturer may dictate or varying uses may demand.

Having thus described my invention, what 40 I claim and desire to secure by Letters Patent is—

1. An advertising device of the character described comprising a front plate, an intermediate plate, a rear plate, the intermediate plate having a cut out portion forming a recess between the front and rear plates, a picture on the front plate, the front plate having openings therein registering with certain facial portions of said picture, a plate 45 in the recess of the intermediate plate having portions of a picture printed thereon to register with the openings in the front plate, and means movable in a direction transversely of and longitudinally of the front plate and having connection with the plate in the recess of the intermediate plate whereby to impart movements in different directions to the plate in the recess.

2. An advertising device of the character described comprising a front, a rear and an intermediate plate, the intermediate plate having a rectangular shaped recess formed 55 therein, a plate vertically movable in said recess, and having a recess therein, a second

plate laterally movable in said recess, a picture on the front plate, the front plate having openings formed therein in register with certain portions of the picture, means for imparting movement to the two plates disposed within the recess of the intermediate plate in a vertical and in a lateral direction, and portions of a picture printed on the last named movable plate adapted to register with the openings in the picture on the front 75 plate.

3. An advertising device of the character described comprising a front, a rear and an intermediate plate, the intermediate plate having a rectangular shaped recess formed therein, a plate vertically movable in said recess, and having a recess therein, a second plate laterally movable in said last mentioned recess, a picture on the front plate, the front plate having openings formed 80 therein in register with certain portions of the picture, and also having another opening therein, a block secured to said last named plate and projecting through the last mentioned opening in the front plate, a calendar 85 attached to said block and covering the block and the opening through which the block projects, said calendar and the block being adapted to impart movement to the two plates disposed within the recess in the intermediate plate in a vertical and in a lateral direction, so as to register portions of the picture printed on said last named plate with the first mentioned openings in the front 90 plate.

4. A device of the character described comprising a front, an intermediate and a rear plate, the intermediate plate having a rectangular shaped opening formed therein, a pair of movable plates in said recess, one 95 movable in a vertical direction and one movable both in a vertical and in a lateral direction, a picture printed on the front plate, the front plate having openings in register with certain portions of the picture, printed matter on one of the movable plates registering with the openings in the front plate, and means for imparting movement to the movable plates.

5. A device of the character described comprising a front, an intermediate and a rear plate, the intermediate plate having a rectangular shaped opening formed therein, a pair of movable plates in said recess, one 110 movable in a vertical direction and one movable both in a vertical and in a lateral direction, a picture printed on the front plate, the front plate having openings in register with certain portions of the picture, printed matter on one of the movable plates registering 115 with the openings in the front plate, the front plate also having a rectangular shaped opening therein, a block attached to one of the movable plates and projecting through said opening, and means attached to said 120 125 130

block and forming a closure for said opening, and adapted to impart movement to both of the movable plates.

6. A device of the character described comprising a front plate having an upper set of openings and a lower opening, an intermediate plate and a rear plate, the intermediate plate having a cutout portion forming a recess between the front and rear plates, the front plate having a picture on its exposed face in register with which picture the upper set of openings in the front plate register, a plate in the recess between the front and rear plates provided with portions of a picture printed thereon and disposed in register with the upper set of openings in the front plate, the plate located in said recess having movement in different directions, and means movable over the exposed face of the front plate and having connection through the lower opening of the front plate with the plate in said recess whereby to impart movement to the plate in

the recess and thereby operate the facial portions of the plate and the recess over the upper set of openings in the front plate.

7. An advertising device of the character described comprising a front plate, a rear plate, there being a recess formed between the front and rear plates, the front plate having a picture on its exposed face and also having openings therein in register with certain facial portions of the picture, a plate in the said recess mounted for movement in different directions and having portions of a picture printed thereon to register with the openings in the front plate, and means having connection through the front plate with the plate in the recess and movable over the exposed face of the front plate whereby to impart movement to the plate in the recess and thereby operate the portions of the picture on the plate in the recess over the openings in the front plate.

ALBERT F. WARD.
